UNITED STATES PATENT OFFICE.

FRANCIS H. SHEPHERD AND JOHN W. MEYER, OF DAVENPORT, IOWA.

TAG FOR WALL-PAPER, &c.

SPECIFICATION forming part of Letters Patent No. 279,192, dated June 12, 1883.

Application filed April 2, 1883. (No model.)

To all whom it may concern:

Be it known that we, FRANCIS H. SHEPHERD and JOHN W. MEYER, citizens of the United States, residing at Davenport, in the county 5 of Scott and State of Iowa, have invented a new and Improved Wall-Paper and Border Tag, of which the following is a full, clear, and exact description, reference being had to the annexed drawings and letters of reference 10 marked thereon, forming a part of this our specification of said invention, in which drawings—

Figure 1 is a perspective view of our improved tag applied to a roll of wall-paper, the 15 view showing the tag partially inserted in position in the roll. Fig. 2 is a central longitudinal section of the tag, and Fig. 3 a perspective view of the same. Fig. 4 indicates the body of the tag made entirely of metal. 20 The object of our invention is the production of a tag suitable for either marking or numbering or exhibiting the price of a roll of either wall-paper or borders, and which can readily be applied either to a roll of wall-paper 25 or a roll of border-paper and detached therefrom, as occasion may require.

Heretofore tags for wall-paper and borders have been applied thereto by tying the tag upon the roll, or by pieces of paper attached 30 with mucilage, or by other means, showing either a given number signifying the character or quality of the roll or the price of a given roll; but this plan of designation was not only troublesome to carry out, but often resulted in 35 mutilating the paper roll. By our invention these disadvantages are avoided and a tag produced which can in a moment be attached to the exposed end of a roll of either wall-paper or borders, and so be displayed to view, while 40 the rolls are packed in the several apartments of the racks employed by paper hangers and dealers for holding the same in their ware-rooms.

In Figs. 1, 2, and 3, A indicates a disk of 45 thick, stiff paper with perforations, as at a, through it and with a wire, as B, passed through the same, the wire in its normal condition being spread apart, as shown in Figs. 2, 3, and 4, so as to require a compression of its extremities b' b', in order to insert the tag in the central opening, c, which always exists in a roll 50

of wall-paper or in a roll of border-paper, as indicated in Fig. 1.

D indicates a disk of thin paper, corresponding in size with A, and attached thereto, as 55 shown, with glue or mucilage, after the wire B has been inserted through the disk A; and upon the exposed surface of the disk D any desired number—as, for example, 35 or 50 or any other number designated by figures is 60 printed—the same being put thereon to designate the price per roll of any particular roll of a lot of rolls, or the quality of the particular roll to which the tag may be applied.

It will be seen that by simply compressing 65 the extremities b' of the tag, the tag may readily be inserted into the central opening, c, of the roll of wall-paper or border-paper F, as the case may be, and that the springy action of the wire B to resume its normal condition, 70 as shown in Figs. 2 and 3, will hold the tag in position in the roll, and this without in the least injuring the roll of paper; and, further, that the roll may be unrolled to exhibit the same to a customer without removing the tag. 75 In Fig. 1 the tag is shown partially inserted in position; but when wholly so the rear of the disk A will abut against the end of the roll, while at the same time, by reason of rigidly attaching the bowed portion of the wire to the 80 metal plate, and also constructing the prongs of the wire B of springy metal and flared, as shown in Figs. 2 and 3, said prongs, when inserted into the hollow center of the roll of paper, as shown in Fig. 1, will have a spring 85 action at the disk-connection and away therefrom, and thus press against the interior of said roll, so as to effectively hold the tag in position therein by a spring frictional contact extending the entire length of the prongs. 90

The advantage of our improved tag for wall-paper and borders is apparent, in that the same can be readily attached to or detached from a roll, in that it will in no way mutilate or disfigure the same, and can remain in position in a roll while the roll is unwound in order to exhibit the same to a customer, and so not liable to become lost or misplaced during such act. 95

It will also be seen that the dealer, by marking his samples with a number corresponding with the number of a given tag, can find the 100

pattern needed in an instant, and that the number of his goods will be preserved and held in place until the last yard of border or paper is sold. The part A need not be in disk form.

5 Any other proper form will answer—as, for example, either square or oblong. We therefore do not confine ourselves to any particular form of the part A; neither do we confine ourselves to the use of stiff paper from which to make the part A; nor to the puncturing of the same at *a a*, for the insertion of the wire B, as the part A may be made of tin or other proper metal, and the bow *b²* of the wire be soldered thereto upon one of its surfaces, while paper D, with number thereon, may be affixed to its opposite surface, or the number of the tag may be painted upon such surface.

10 Fig. 4 indicates the part A as consisting of metal, with the wire B attached thereto by solder *f*, applied upon the bow *b²* of the wire and the rear surface of the part A.

15 We are aware that heretofore a tag has been constructed with pointed sharp-ended arms to pass through the index-face of the tag and then through a piece of cloth, to which it is held by turning down the sharp-pointed arms upon the cloth; but this we do not claim.

20 Our tag is specially adapted for use in connection with rolls of wall-paper and borders, and the tag is held in the central opening there- 30 in by the expansion or spring action of its holding-wire, and does not pierce the fabric in order to be held in place, and therefore is not liable to injure the fabric to which it is applied.

25 Having thus described our invention, what we claim as new, and desire to secure by Letters Patent, is—

1. In a wall-paper and border tag, the combination, with the index-plate A, of the springy- 40 metal pronged wire B, with flaring ends and rigidly fastened to the said plate, whereby the prongs are caused to exert a spring-holding action upon the roll of paper or border when inserted into the same, substantially as de- 45 scribed.

2. The combination, with the index-plate A, of the springy-metal pronged wire B, the prongs being flared, substantially as described.

FRANCIS H. SHEPHERD.
JOHN W. MEYER.
